JOHN T. JONES AND GEORGE W. JONES, OF WESTERN PORT, MARYLAND.

BARK-PEELING MACHINE.

SPECIFICATION forming part of Letters Patent No. 593,897, dated November 16, 1897.

Application filed January 28, 1897. Serial No. 621,042. (No model.)

To all whom it may concern:

Be it known that we, JOHN T. JONES and GEORGE W. JONES, of Western Port, in the county of Allegany and State of Maryland, have invented a new and useful Improvement in Bark-Peeling Machines, of which the following is a specification.

Our invention is in the nature of an improved machine for peeling or cutting the bark from logs preparatory to cutting up said logs into chips in the manufacture of wood-pulp for paper-making. Machines for doing this work have heretofore been invented; but the difficulty heretofore experienced is that the machines for doing this work either cut away and waste a considerable portion of the wood or else work so very slowly as to have no advantage over hand-peeling. Our invention is designed to accomplish the work very rapidly and expeditiously and at the same time to avoid any wasteful cutting of the wood fibers; and to this end it consists in an improved construction and arrangement of parts, which we will now proceed to fully describe with reference to the drawings, in which—

Figure 1 is a vertical cross-section through the machine. Fig. 2 is a vertical longitudinal section of one end of the machine; Fig. 3, a plan or top view, and Fig. 4 a sectional detail, of one of the cutter-heads.

In the drawings, Fig. 1, A A' A² represent a strong framework, to the outer ends of which on the middle line are attached upright bars or standards A³, which extend from the lower frame-bar A to a point some distance above the upper horizontal frame-bar A². Between these standards A³ and extending from one end to the other of the machine there is arranged a horizontal log-table B, which has an extension at each end that passes through a slot s in the vertical standards and is provided with a large and strong screw-nut b, Fig. 2, that embraces a vertical screw-rod C at each end of the machine, and by the rotation of which screw-rod the log-table is raised and lowered and guided in its adjustment.

In bearings on each side of the table are arranged parallel to each other shafts B⁸ B⁸. These shafts have at each end small toothed wheels B' B', upon which the log rests and by

which the log is slowly rotated while the bark is being cut off. There is one pair of these wheels near one end of the machine and another pair near the other end, and as the log only bears upon these four wheels the log, even if it be crooked, will always find a bearing thereon and be rotated thereby. To give rotary motion to these wheels and shafts, the latter are extended at their ends beyond the framework and have sprocket-wheels B² fixed to them, and with these sprocket-wheels there engages at each end of the machine an endless chain belt B⁴, which also passes around a lower sprocket-wheel B³ on a shaft B⁷ near the bottom of the machine and also an upper sprocket-wheel B⁵ on a shaft B⁶, journaled in bearings in the top of the end standards A³. This shaft B⁶ has a loose and tight pulley P P', so that a drive-belt may be shifted from one to the other, according as it is desired to rotate the log or hold it still. These two pulleys P P' are shown in Fig. 2 inside the framework, but they may be placed at any convenient place either inside or outside the framework.

As the log is turned its bark is stripped off by two series of cutter-heads D (see Fig. 3) on opposite sides of the middle line, one series of cutter-heads alternating with the other series, so that one series of cutter-heads takes off a series of rings of bark and the other series strips the intervening portion, so that a single revolution of the log about its longitudinal axis causes it to be entirely stripped of its bark. Each of the cutter-heads is arranged to revolve in a separate frame D', which about its middle is hung loosely upon a horizontal shaft D². A band-pulley d² is rigidly fixed to this shaft D² within each frame D', and a band d' connects it with a smaller band-pulley d, fixed to the side of each cutter-head, so that the rotation of the shaft D² is made to impart a rapid rotation to each of the cutter-heads, while each cutter-head and its frame is adapted to rise and fall independent of the rest, according to the inequalities or curves of the log. To hold the cutter-heads against the log with a gentle pressure, the outer ends of the swinging frames D' are held between spiral springs d³ d⁴, (see Fig. 1,) arranged between the horizontal rods D³ D⁴, placed one above the other.

- To impart motion to the shafts D^2 that drive the cutter-heads, a band-pulley D^7 (see Fig. 3) is fixed upon one of said shafts, and the two shafts $D^2 D^2$ are connected together 5 for a reversed rotation by band-pulleys $D^5 D^5$ on the ends of the same and a crossed belt D^6 . This gives a reversed rotation to the series of cutter-heads on opposite sides of the log and secures an important result, in that the pull 10 of one set of cutter-heads on the log is neutralized by that of the other set. If the pull of all the cutter-heads on the log were in the same direction and acting at the same time, it would interfere with the action of the log- 15 turning devices to such an extent as to prevent the latter from acting properly and would also cause the chips of one set of cutter-heads to clog and impair the action of the other cutter-head.
- 20 To raise and lower the log-table, the screw- rods C are turned within the nuts b on the extension of the table, and this rotation of these rods is effected through a bevel-gear $c' c^2$ at each end of the machine, the bevel-gears c' 25 being on the upper ends of the screw-rods C , while the intermeshing bevel-gears c^2 are upon the ends of a horizontal shaft C' , which may be turned either by hand or by machinery through a tight and loose pulley. As the log- 30 table is raised and lowered it will be seen (see Fig. 1) that the log-turning sprocket-wheels B^2 rise and fall within the chain belts B^4 , which still maintain their engagement with the said sprocket-wheels.
- 35 To make use of our invention the log-table B is lowered to its lowest position and the log from suitable skids or log-rolling devices is rolled sidewise over the toothed wheels B' on that side, and the table is then raised until 40 the log is brought into contact with the cutter-heads above, and as the log is turned axially in contact with the cutter-heads the bark is quickly and perfectly stripped therefrom without waste of wood.
- 45 In constructing the cutter-heads (see Fig. 4) the knives k are arranged diagonally, and one side of the cutter-head is concaved or hollowed out at k^2 and is made to communicate with the throats k' in front of the knives, 50 so that the chips of bark that pass into the throats have a lateral clearance from the cutter-heads.
- Having thus described our invention, what we claim as new, and desire to secure by Letters Patent, is—
- 55 1. The combination with cutter-heads arranged above the log; of a subjacent log-supporting table, turning devices consisting of a horizontal shaft on each side of the table provided with supporting-wheels and sprocket-wheels on their ends, an endless chain belt passing around said sprocket-wheels, and dis-

tending and actuating wheels for the chain belt one arranged above and the other below the log-table, and means for adjusting the table and its turning devices vertically substantially as and for the purpose described. 65

2. The combination with cutter-heads arranged above the log; of a subjacent log-supporting table, turning devices consisting of a horizontal shaft on each side of the table provided with supporting-wheels and sprocket-wheels on their ends, endless chain belts passing around said sprocket-wheels, distending and actuating devices for the chain belt, 70 and a vertical adjusting-screw at each end of the table in mesh with nuts on the ends of the table and arranged to adjust the latter vertically substantially as and for the purpose described. 75

3. In a bark-peeling machine the combination of the main frame having slotted end standards A^3 ; of a log-table provided with supporting and turning devices consisting of shafts $B^3 B^8$, wheels $B^7 B^2$, and chain belt B^4 , 85 and also a screw-nut b at its ends, the screw-rods C , bevel-gears $c' c^2$, and operating-shaft C' substantially as and for the purpose described. 80

4. The combination with a set of log turning and supporting devices; of two series of yielding cutter-heads arranged upon independent axes alternately upon opposite sides of the middle of the log-table, with the cutter-heads of one set alternating with those of the other set and revolving in opposite directions to cause the pull of one set of cutter-heads on the log to neutralize that of the other set substantially as and for the purpose described. 95

5. The combination with a set of log turning and supporting devices; of a set of yielding cutter-heads arranged upon independent axes alternately upon opposite sides of the log-table and resting against the log and following its inequalities substantially as and for the purpose described. 100

6. In a bark-peeling machine the combination with the log supporting and turning devices; of a horizontal shaft D^2 carrying a series of rigid drive-pulleys d^2 , a series of cutter-heads and actuating devices consisting each of a horizontal frame D' hinged upon said shaft D^2 and carrying at its end, a cutter-head D with drive-pulley d , the belt d' connecting said pulleys d^2 and d' and springs d^3 and d^4 arranged above and below the outer ends of the hinged frames D' substantially as and for the purpose described. 110
